GUSTAVE E. MEYER, OF NEW MEADOWS, IDAHO.

HANGER FOR LEAF TURNERS.

Application filed October 1, 1926. Serial No. 138,985.

This invention relates to hangers for leaf turners and the object of the invention is to provide a hanger which may be easily removed from or attached to a leaf-turning arm for securing the side edge of a leaf to hold the same against disturbance under the influence of air currents. Heretofore leaf turners have been provided including essentially a plurality of pivotally mounted arms equipped with means for securing the leaves of a musical composition or of a book and actuating springs connected with the arms whereby, when the arms are successively released, they will be automatically swung about their pivots so that the leaves or sheets will be swung to the opposite side of a supporting frame. When the leaves of a book are being thus turned, the inner edges of the leaves will be held against separation by the binding of the book but when sheet music is being turned, especially when the composition comprises a single sheet, it is often desirable to retain the side edge of the sheet against movement away from the supporting frame, and the object of my invention specifically stated is to provide a device for this purpose which may be easily and quickly applied to the leaf-turning arm when desired and as easily and quickly detached when its use is not necessary. The invention is illustrated in the accompanying drawing and will be hereinafter fully set forth.

In the drawing:

Figure 1 is a front elevation of so much of a leaf-turning mechanism as is necessary to impart an understanding of the invention;

Fig. 2 is an enlarged detail vertical section through the upper portion of the hanger and the structure whereby it is engaged with the leaf-turning arm;

Fig. 3 is a bottom plan view of the lower end of the hanger, and

Fig. 4 is a detail view of an upper clasp.

In the drawing, the reference numeral 1 indicates a portion of the supporting frame which may be a music stand or a supplemental frame adapted to be placed upon a piano desk. 2 designates portions of turning arms which are pivotally mounted upon a post 3 secured upon the frame 1 and respectively actuated by springs 4 to be turned to the left as may be necessary during the rendition of a composition. The turning arms 2 are normally held at the right of the pivot post 3 by latches or other devices which are

released to permit the turning of the arms under the influence of the respective springs 4, these latches and the means for releasing them not being shown in the drawing inasmuch as they do not form a part of the present invention. In the particular form of turning arms illustrated, each turning arm terminates at its inner end in a yoke 5 which has its ends fitted about the post 3 and to which one end of the respective spring 4 is attached. On that arm which is the outermost when all the arms are at the right, there is provided a depending socket 6 which may be formed integral with the yoke 5. This socket is preferably flat sided to receive the upper flattened end member 7 of a hanger which includes a shank 8 of a sufficient length to extend downwardly to a point where engagement with the leaf to be turned will suffice to hold the leaf flat against the music stand or the supporting frame. The shank 7 is formed with an opening 9 therethrough adapted to register with a similar opening 10 in the front wall of the socket 6 and a leaf spring 11 is secured at its upper end to the socket and is provided near its lower end with a latch pin or stud 12 adapted to enter the aligned openings 10 and 9 so that the terminal 7 will be retained in the socket, as shown in Fig. 2. The lower extremity of the spring 11 is offset, as shown at 13, whereby a finger of the operator may be easily inserted behind the spring when it is desired to permit withdrawal of the hanger. The terminal 7 may, of course, be integral with the shank 8 of the hanger, but I prefer to provide the shank with an enlarged socketed lower end 14 in which the shank may be secured in any well-known manner. This construction permits the use of ordinary wire for the shank and thereby effects an economy in manufacture.

At the lower end of the shank is a leaf-engaging clasp consisting of the jaws 15 and 16 which are pivotally connected, as indicated at 17, and have their free ends normally pressed together by a spring coiled about the pivot in a well-known manner, the spring not being shown in the present drawing for the sake of clearness in the illustration. The jaw 16 is provided with an eye 18 receiving the lower end of the shank 8 and being secured thereto by any approved means. On their opposed faces, the free ends of the jaws 15 and 16 are equipped with clamping pads 19 of felt or some similar

material which will firmly clasp the edge of a leaf, indicated at 20, without mutilating the leaf in any way.

When the use of the improved hanger herein disclosed is not necessary, the free end of the spring latch is shifted outwardly sufficiently to withdraw the pin or stud 12 from the opening 9, whereupon the hanger will at once drop from the socket 6. If the use of the hanger is desirable, it is necessary merely to insert the end of the terminal 7 upwardly within the socket 6 and permit the pin 12 to engage the opening 9, whereupon the hanger will be firmly held in place. The flattered construction of the socket and the terminal member engaged therein serves to guide the terminal when it is being inserted and also prevent relative rotation of the terminal so that the clasp for engaging the leaf will be always placed in proper position to serve its purpose. The device is exceedingly simple and will not add any appreciable weight to the leaf-turning arms so that the arms will turn freely under the influence of their respective springs just as though the hanger were not employed. While I have illustrated the hanger as applied to one of the leaf-turning arms, it is obvious that all the arms may be constructed to receive the hangers and when a composition extending

over a number of loose sheets is being played a plurality of hangers may be provided without interfering with the operation of any of the other parts.

Generally, a single clasp at the lower end of the hanger will be sufficient but it is desirable frequently to hold the upper corners of the sheets or leaves. For this purpose, I provide an upper clasp 21, similar to the lower clasp and having pads 22 corresponding to the pads 19. To the jaws of the upper clasp are attached retainers 23 in the form of stout wires extending upwardly in converging relation to engage the opposite sides of the leaf and prevent curling thereof, as will be understood on reference to Fig. 4.

Having thus described the invention, I claim:

A leaf-turning arm provided with a depending socket, a hanger engageable in the socket and having an opening through its end portion, a leaf spring secured at one end upon the socket and having its free end extending beyond the socket, and a latch pin carried by said spring and engageable through the socket and the opening in the end member of the hanger.

In testimony whereof I affix my signature.

GUSTAVE E. MEYER. [I. S.]
